UNITED STATES PATENT OFFICE

FRED F. LEMOINE, OF MAYNARD, MASSACHUSETTS

DESIGN FOR A HOLDER FOR ASH TRAYS OR OTHER ARTICLES

Application filed November 3, 1932. Serial No. 45,726. Term of patent 14 years.

To all whom it may concern:

Be it known that I, FRED F. LEMOINE, a citizen of the United States, and a resident of Maynard, in the county of Middlesex and State of Massachusetts, have invented a new, original, and ornamental Design for a Holder for Ash Trays or Other Articles, of which the following is a specification, reference being had to the accompanying drawing, forming part thereof.

Referring to the drawing:

Fig. 1 is a side elevation of a holder showing my new design;

Fig. 2 is a front elevation of said holder; and

Fig. 3 is a top plan view of said holder.

The shading in the drawing is to illustrate contrasting colors.

I claim:

The ornamental design for a holder for ash trays or other articles, substantially as shown and described.

In witness whereof, I hereunto subscribe my name this 2nd day of November, A. D. 1932.

FRED F. LEMOINE.
